T E M^o Neill

Hydraulic Press.

N° 59853.

Patented Nov 20, 1866.

United States Patent Office.

IMPROVEMENT IN COTTON PRESS.

THOMAS E. McNEILL, OF LYNCHBURG, VIRGINIA, ASSIGNOR TO HIMSELF AND WILLIAM D. MILLER, OF THE SAME PLACE.

Letters Patent No. 59,853, dated November 20, 1866.

SPECIFICATION.

TO ALL WHOM IT MAY CONCERN:

Be it known that I, THOMAS E. McNEILL, of Lynchburg, in the county of Campbell, and State of Virginia, have invented a new and improved Cotton Press; and I do hereby declare that the following is a full, clear, and exact description thereof, reference being had to the accompanying drawings forming part of this specification:

The nature of my invention has for its object the pressing of cotton into bales, and is worked by hydraulic pressure, and consists in making two hydraulic presses and working them in conjunction with each other, or separately, as may be desired.

Various kinds of hydraulic presses have been constructed and used at an enormous expense. By reason of their complication and liability of breaking and getting out of order, serious objections have been urged against them. The simplicity and utility of my invention overcome these objections.

To enable others skilled in the art to make and use my invention, I will proceed to describe its construction and operation.

The figure represents a front elevation of my improved cotton press. Letters of like name and kind refer to like parts in the figures.

A represents the foundation on which stands my improved press.

B is a boiler of common construction, and stands in a vertical position, to which is attached a small vertical steam engine, C, which receives its steam which is generated in the boiler B.

D is the piston of the engine, which is connected to the lever E, which has a bearing at F made upon the standard post G, which is secured to the reservoir or pump H.

I is a pipe that leads into the cylinder J, which is connected to the press K by the piston L. The said pump, K, is guided in the posts M M.

N is a pipe leading from the cylinder J to the cylinder O, which is secured and stands upon the foundation P.

This cylinder, O, is provided with a piston, which is attached to the press Q, which works up and down upon the rods R R R R, two of which are not shown in the drawings.

S is the top of the press secured to the said posts R. These heads of this press are provided with grooves in which to lay the ropes or bands while the cotton is undergoing the action of the press, and so arranged that the bales may be bound while the action of the press is going on.

T is a pipe leading from the pumps H to and connects with the pipe N.

U U are valves placed in the pipes N and T, and so placed that a continuous stream of water is forced into the cylinder O.

V is a stop-cock located in the pipe I for the purpose of cutting off the water and preventing it from entering the cylinder J.

Having thus described my invention, what I claim as new, and desire to secure by Letters Patent, is—

1. The cylinder J, pipes I and N in combination with the cylinder O, for the purposes and substantially as herein shown.

2. I claim cylinder J, piston L, in combination with the press or follower K, substantially as described.

3. I claim a hydraulic press provided with or constructed with two cylinders, so as to operate or act in conjunction with each other, or separately, when constructed and operated for the purposes and substantially as described.

THOMAS E. McNEILL.
